PROJECTILE

Bernard H. Bayler, Richmond, Va.

Application August 3, 1940, Serial No. 350,835

5 Claims. (Cl. 102—29)

My invention relates to improvements in projectiles.

An important object of the invention is to provide a projectile which is a combination shrapnel-shell for anti-aircraft artillery, field artillery, and the like.

A further object of the invention is to provide a shrapnel-shell having two bursts on the same trajectory, allowing a considerable distance between the bursts, rendering it easier to strike the target.

A further object of the invention is to provide a shrapnel-shell of the above-mentioned character which will impart an increased velocity to the shrapnel and a wider angle of scatter.

Other objects and advantages of the invention will be apparent during the course of the following description.

In the accompanying drawing forming a part of this application and in which like numerals are employed to designate like parts throughout the same:

Figure 1 is a central vertical longitudinal section through a shrapnel-shell embodying my invention,

Figure 2 is a horizontal section taken on line 2-2 of Figure 1.

Figure 3 is a similar view taken on line 3-3 of Figure 1.

Figure 4 is a similar view taken on line 4-4 of Figure 1, and

Figure 5 is a side elevation of the rear end of the projectile case, parts broken away.

In the drawing, wherein for the purpose of illustration is shown a preferred embodiment of my invention, the numeral 10 designates the case of the projectile, having a closed rear end 11 provided with a chamber 12 for receiving a charge of black powder 13, which is employed to project the shrapnel from within the case. The case 10 may be formed of steel.

disposed at the forward end of the steel case is a steel head 14, secured thereto by pins 15, which will break upon the exploding of the powder charge 13 to permit of the head 16 being blown from the case 10. The head 14 carries a fuse 16, which may be a time and percussion fuse. This fuse has a cylindrical tubular part 17 engaging within a screw-threaded opening 18, formed in the head 14.

Arranged within the steel case 10 is an inner tube or barrel 19, of smaller diameter than the case 10 and arranged in spaced concentric relation therewith, providing an annular passage or chamber 20. This annular chamber receives the

explosive charge 21 which bursts the case and barrel 19 after the shrapnel has been projected therefrom. This charge is preferably nitro-cellulose powder. At its rear end, the barrel 19 is screwed into a recess 22 of the case 10, as shown. The bore of the recess 22 has a diameter smaller than the bore of the case 10, forming a shoulder 22^a while the chamber 12 has a bore smaller than the recess 22, forming a shoulder 22^b. The barrel 19 is screwed down to firmly engage the shoulder 22^b whereby the rear end of the chamber 20 is closed and has no communication with the interior of the barrel 19. At the forward end of the barrel 19 is a bronze bushing 23, which has screw-threaded engagement within the case 10. This annular bronze bushing covers the forward end of the annular chamber 20 and terminates flush with the inner wall of the barrel 19 and has studs or prongs 23' which project inwardly beyond the inner face of the barrel 19. These studs or prongs preferably taper so that they will not interfere with the proper discharge of the shrapnel. There is a shim 19' of paper or the like, clamped between the free end of the barrel 19 and the bushing 23. Arranged centrally within the barrel 19 is an ignition tube 24, holding a burning composition and the rear end of this tube is anchored in an opening 25 formed in a steel diaphragm or disk 26, arranged at the rear end of the barrel 19 and covering the chamber 12. The tube 24 leads into the chamber 12. The tube 24 at its forward end also leads to the interior of the cylindrical tubular part 17 of the fuse, passing through an opening 17', formed in the end wall 18'. This tube 24 is removably mounted in the opening 17'. The time and percussion fuse ignites the burning material in the tube 24, in accordance with the usual practice.

The barrel is filled with shrapnel in the form of shot or slugs 21.

The barrel 19 is provided near its forward end with vents 28 leading into the forward end of the annular chamber 20 which is filled forwardly of the explosive charge 21 with a slow burning composition 29, at the rear of which is a primer 29' of black powder.

The shell case 10 is provided with a soft copper rotating band 30, rigidly secured thereto, the material of which is forced into the grooves of the rifled barrel, to produce a gas-tight fit when the projectile is fired. This band is shown as equipped with three gradual depressions 31, extending longitudinally of the case 10 from the rear 55 to the forward edge of the band 30. The depressions 31 are provided to facilitate the removal of the shell case 10 from the barrel.

sion 31 is about $\frac{1}{64}$ of an inch in depth, the same being somewhat exaggerated in the drawing.

In Figure 5, I have shown the case 10 as equipped with a soft copper rotating band, corresponding to the band 30, and having inclined or slanting grooves 33, arranged beneath the same. These grooves are formed in the case 10, and are preferably $\frac{1}{64}$ of an inch deep, and these grooves extend beyond the forward and rear edges of the band.

The depressions 31 and grooves 33 permit of the entering of a small amount of air into the barrel of the gun in the rear of the projectile.

The operation of the projectile is as follows:

The projectile is introduced into the barrel of the gun and shot from the same by the explosive charge in the barrel. The fuse 16, time or percussion, when exploding, ignites the burning material in the tube 24 which in turn ignites the black powder charge 13. When this charge explodes, the head 14 is blown from the case 10, and the diaphragm or disk 26 is projected forwardly within the case 10 and stops when it engages the bronze bushing 23. The explosion of the powder charge 13 projects the shrapnel 27 from within the case and their angle or spread increases when the disk or diaphragm 26 engages the studs or prongs 23' of the bronze bushing 23 and is suddenly stopped thereby. After the shrapnel 27 has been projected from the case 10, the slow burning composition 29 ignites the black powder primer 29', in turn causing the nitro-cellulose powder 28 to explode, thereby bursting the case 10 and barrel 19.

It is to be understood that the form of my invention herewith shown and described is to be taken as a preferred example of the same and that various changes in the shape, size, and arrangement of parts may be resorted to without departing from the spirit of my invention or the scope of the subjoined claims.

Having thus described my invention, what I claim is:

1. A projectile comprising a case, an explosive charge in the rear end of the case, a diaphragm covering the explosive charge, a bushing arranged within and secured to the case adjacent to its forward end to stop the forward movement of the diaphragm, a fuse element, a head carrying the fuse element and secured to the forward end of the case by readily breakable means, a tube leading at its forward end into the fuse element and at its rear end to the explosive charge within the case, a second explosive charge to explode the case after the explosion of the first explosive charge, and shrapnel filling the case between the diaphragm and head.

2. A projectile comprising a case having its rear end closed, an explosive charge held within the rear end, a barrel arranged within the case and attached at its rear end to the case, said barrel having a smaller diameter than the interior diameter of the case to provide a chamber surrounding the barrel, the rear end of the chamber being free from communication with the interior of the case, said barrel being provided adjacent to its forward end with vents, an explosive charge within the said chamber, a slow burning composi-

tion within the forward end of the said chamber adjacent to the vents, a primer adjacent to the slow burning composition, a bushing arranged within and secured to the case adjacent to its forward end and extending inwardly into the barrel, a head having a breakable connection with the forward end of the case, a fuse element carried by the head, a tube extending through the barrel and having its forward end leading into the fuse element and its rear end in communication with the first named explosive charge, and shrapnel filling the barrel.

3. A projectile comprising a case having a bore and its rear end closed and provided at the rear end with a chamber having a smaller diameter than the diameter of the bore of the case for affording a shoulder, a barrel arranged within the case and having an exterior diameter considerably smaller than the diameter of said bore, said barrel having its rear end in screw-threaded engagement with the case adjacent to the shoulder, the barrel forming a chamber with the case which chamber is closed at its rear end adjacent to the shoulder, said barrel having vents adjacent to its forward end, an explosive charge within the rear chamber, a second explosive charge within the second chamber between the barrel and case, a slow burning composition within the second chamber adjacent to the vents, a diaphragm within the barrel adjacent to the shoulder, a head having a breakable connection with the forward end of the barrel, a fuse element mounted upon the head, a tube leading into the fuse element and to the first named charge, and shrapnel held within the barrel.

4. A projectile comprising a case, an explosive charge within the case, a diaphragm covering the explosive charge and having an opening formed therein, means carried by the forward portion of the case to stop the movement of the diaphragm with relation to the case when engaging said means, shrapnel arranged within the case in advance of the diaphragm, a time and percussion fuse carried by the case, a tube having both ends open and arranged within the case and having its forward end in communication with the fuse and its rear end passing through the opening in the diaphragm and in communication with the explosive charge, a second explosive charge to burst the case after the explosion of the first charge, and a slow burning composition within the case and arranged to be ignited by the bursting of the first charge to subsequently explode the second charge.

5. A projectile comprising a case, shrapnel within the case, a diaphragm within the case at the rear of the shrapnel, means carried by the forward portion of the case to stop the movement of the diaphragm with relation to the case when engaging said means, an explosive charge within the case behind the diaphragm, a second explosive charge within the case to burst the case, and means carried by the case and timed in operation to first explode the first named charge and subsequently explode the second named charge.
